UNITED STATES PATENT OFFICE.

WILLIAM C. SHAFFER AND ARTHUR M. WHITE, OF PHILADELPHIA, PENNSYLVANIA, ASSIGNORS TO THE RAILROAD SAFETY LOCK AND SIGNAL COMPANY, OF NEW JERSEY.

AUTOMATICALLY STOPPING TRAINS AND SIGNALING.

SPECIFICATION forming part of Letters Patent No. 276,905, dated May 1, 1883.

Application filed January 2, 1883. (No model.)

To all whom it may concern:

Be it known that we, WILLIAM C. SHAFFER and ARTHUR M. WHITE, both citizens of the United States, residing in the city and county of Philadelphia, State of Pennsylvania, have invented a new and useful Improvement in Automatically Stopping Trains and Signaling, which improvement is fully set forth in the following specification and accompanying drawings, in which—

Figure 1 is a rear view of apparatus embodying our invention in position on a locomotive-engine. Fig. 2 is a side elevation thereof.

Similar letters of reference indicate corresponding parts in the two figures.

Our invention consists of means, substantially as hereinafter described, attached to a locomotive-engine, whereby, in the event of danger along the railroad, steam is automatically shut off from the cylinders of the engine and the brakes are applied, thus stopping the train, the whistle also being operated, thus signaling the danger, these results being accomplished without abruptness.

Referring to the drawings, A represents one of the axles of a locomotive-engine, and B represents the box thereof.

C represents an upright leg, which, pivoted to the box A, is adapted to be engaged by a projection, foot, or shoe, C', located along the line of the railroad, and supported on sleepers, ties, or other proper means in the road-bed.

D represents a lever, which is mounted on a suitable portion of the engine adjacent to the box B, and its lower end is pivoted to a lever, E, which extends horizontally, and has a longitudinally-extending slot, a, in which projects a pin or stud, b, of the leg C. The upper end of the lever D is adapted to engage with one

limb of an elbow-lever, F, which is mounted on a shaft, G, the bearings of which are on a suitable portion of the engine, said shaft also carrying a pulley, J, around which passes a belt, cord, or chain, K, one end of which is

connected with a drum, L, whose bearings are on the upper limb of the elbow-lever F. The other end of the belt K is connected with the levers A'A'', respectively, of the throttle-valve and whistle.

To one of the limbs of the elbow-lever F is pivoted an arm or rod, M, whose upper end is within convenient reach of the engineer or other person on the engine, so that said lever may be reset and the connected parts assume their normal positions.

N represents a belt, cord, or chain, which is adapted to be wound on the drum L, and, passing around the pulley J, is connected with the air, steam vacuum, or other brake mechanism of the engine or train.

It will be seen that the lever F is so disposed that when it is held by the lever D the drum L overhangs the axle A, and when said lever F is disconnected from the lever D the former gravitates or moves on its axis in such manner as to present said drum L to contact with the axle A, or gear it with the axle and cause rotation of the same, whereby the belt K will be wound on the drum.

The shoe C' may be raised automatically or by hand in the event of danger due to misplaced switches, open draws, broken rails, accidents, &c., it being essential to stop the train.

As soon as the leg C strikes the shoe it is carried rearward by the engaging contact with said shoe, thus moving with it the lever E and causing the tripping of the levers D F. The drum L, coming in contact with the axle A, is positively rotated, whereby the belt K is wound on the former, the effect whereof is to operate the throttle-valve and shut off the steam to the cylinders of the engine, and likewise operate the whistle-lever, thus causing the whistle to blow and signaling the engineer. Simultaneously therewith the strap N is wound on the drum and the brakes thereby applied, the result being the stopping of the train.

Bearing against the back of the leg C is a spring, P, which is attached to the axle-box or frame of the engine, and serves to prevent abrupt motion of the leg when it strikes the projection C', and restore said leg to its normal position after the lever F has been tripped.

By depressing the arm M the lower limb of the elbow-lever rides over the back of the upper part of the lever D until it reaches the head of the latter, when the two levers interlock and the drum L is held clear of the axle A.

Owing to the slot *a* of the lever *E*, when the engine backs and strikes either of the shoes *C'*, the leg *C* is permitted to move toward the front of the engine without imparting motion to the lever *E* and connected parts.

It is evident that the winding device may be automatically geared with any other movable member of the engine than the axle, and the motion of train stopping or signaling mechanism or both will be thereby retarded or governed, so as to be operated without abruptness.

Having thus described our invention, what we claim as new, and desire to secure by Letters Patent, is—

- 15 1. A locomotive-engine provided with a device adapted to engage with a shoe or projection along a railroad, and means connected with said device and the stopping mechanism of the engine, adapted to gear with and receive 20 rotary motion from a movable member of the engine, whereby in the event of danger said stopping mechanism is operated and the engine or train thereby stopped, substantially as stated.
- 25 2. A locomotive-engine provided with a device adapted to engage with a shoe or projection along a railroad, and means connected with said device and the stopping and signaling mechanisms of the engine, adapted to gear 30 with and receive rotary motion from a movable member of the engine, whereby in the event of danger said stopping and signaling mechanisms are operated, thus signaling danger and stopping the train, substantially as stated.

3. The combination, with a movable member of a locomotive-engine, of a drum and connections with the stopping mechanism of the engine, adapted to be wound on said drum, said drum being adapted to be automatically engaged or geared with said member, substantially as and for the purpose set forth.

4. Connections with the stopping mechanism of a locomotive-engine, in combination with a drum for winding said connections, a lever for moving the drum against the axle of the engine, and an automatically-operated tripping-lever for releasing the first-named lever, substantially as and for the purpose set forth.

5. The leg *C* and connecting arm or lever *E*, in combination with the tripping-lever *D*, drum *L*, drum-carrying lever *F*, and connections with the stopping and signaling mechanisms of the engine, substantially as and for the purpose set forth.

6. In automatic train-stopping or train-signaling mechanism, a device adapted to be automatically geared with a movable member of a locomotive-engine for retarding or governing the motion of said mechanism, substantially as described.

WILLIAM C. SHAFFER.
ARTHUR M. WHITE.
